UNITED STATES PATENT OFFICE.

THOMAS H. BURNETT, OF EXCHEQUER, CALIFORNIA.

INTERNAL-COMBUSTION ENGINE.

1,308,621.

Specification of Letters Patent.

Patented July 1, 1919.

Application filed September 24, 1918. Serial No. 255,451.

To all whom it may concern:

Be it known that I, THOMAS H. BURNETT, a citizen of the United States, residing at Exchequer, in the county of Mariposa, State of California, have invented certain new and useful Improvements in Internal-Combustion Engines; and I do declare the following to be a full, clear, and exact description of the same, reference being had to the accompanying drawings, and to the characters of reference marked thereon, which form a part of this application.

This invention relates to improvements in engines and particularly to that type known as internal combustion engines. The object of the invention is to produce an engine which will have a greatly increased power over the present type of engine and at the same time one in which the vibration due to the explosion will be greatly lessened.

In the now commonly used form of internal combustion engines, the reciprocating pistons are movable in fixed or stationary cylinders. The explosion of the fuel of course causes a concussion in all directions. The piston being the only movable part is driven by this concussion but the fixed stationary cylinder receives all the jar of the vibration, but has no movement. Hence, the force of the explosion against the sides of the cylinder walls is lost and it tends to cause an excessive vibration and heat. In my improved type of engine, I provide reciprocating cylinder walls moving in the reverse direction to the piston, such movable cylinder walls having connecting rods connecting them with the crank shaft. The forces of the explosion of the fuel within the engine then drives against the two movable parts and forces one in one direction and the other in the opposite direction. This utilizes the full force of the explosion and at the same time causes the two movable parts to be cushioned with respect to each other to such an extent as to almost eliminate the vibration and to lessen the heat.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claims.

55 In the drawings, similar characters of ref-

erence indicate corresponding parts in the several views.

Figure 1 is a plan view in section of the complete engine.

Fig. 2 is a side elevation of the same. 60

Fig. 3 is a fragmentary sectional view showing the exhaust mechanism.

Referring now more particularly to the characters of reference on the drawings, and in providing my improved invention, I first 65 furnish a base 1 having side walls 2 provided with horizontal slots 3. The numeral 4 designates the cylinder which is provided with projecting flanges 5 movable in the slots 3. Connecting rods 6 connect the end of the 70 cylinder 5 with the crank shaft 7. The piston 8 is movable within the cylinder 4 and is provided with a connecting rod 9 connecting such piston with the crank shaft 7. When the explosion takes place within the 75 cylinder 4, the force of such explosion drives such cylinder in one direction and the piston in the opposite direction. Thus, the full force of the explosion is utilized by reason of the connections with the crank 80 shaft. Also, the cylinder and piston are cushioned one against the other in such a manner as to practically limit all vibration. The cylinder 4 is provided with a valve inlet pipe 10 which is provided with a slip 85 joint as at 11, to allow the reciprocating motion of the said cylinder. The inlet pipe 10 is connected with any suitable form of fuel supply and is provided with a spring inlet valve 12 which opens with the suction within the cylinder and closes when the compression takes place. 90

The engine is of course provided with suitable ignition means to cause an igniting spark in the plug 13, and is provided with 95 an upwardly opening exhaust puppet-valve 14 seated in the head end of the cylinder 4 which is provided with an exhaust port 15. The puppet valve is seated by the usual spring means and is provided on 100 the lower end of its stem with a roller 16 whose lower face is adjacent the top surface of a lever arm 17 fulcrumed to the frame 1, as at 18, the lever arm being forced downwardly by a spring 19 between 105 the lever and the frame, or by a weight 20 on the end of the arm 17, thus causing said arm to always bear against a cam 21 rotatably mounted in the frame 1 and adapted to be turned by any suitable means, not 110

shown, such as will give the cam one revolution to every two revolutions of the crank shaft, as is common practice on four cycle gas engines. The cam 21 is of course so 5 positioned that the valve 14 will be lifted at the correct point in the engine cycles.

While I have shown here a single cylinder engine, the same construction may be used with any number of cylinders. In the 10 same way, the intake valve may be operated mechanically instead of being of the automatic type.

Thus, from the foregoing description, it 15 will readily be seen that I have produced such a device as substantially fulfills the objects of the invention as set forth herein.

While this specification sets forth in detail the present and preferred construction 20 of the device, still in practice, such deviations from such detail may be resorted to as do not form a departure from the spirit of the invention, as defined by the appended claims.

Having thus described my invention, what 25 I claim as new and useful and desire to secure by Letters Patent is:—

1. An internal combustion engine comprising a base, a cylinder slidably mounted

therein, a piston and cylinder being operatively connected with the crank shaft to move in relatively different directions, a 30 spring seated valve adapted to move upwardly, positioned vertically in the underside of the cylinder ahead of the piston, and means independent of the movement of the 35 cylinder, whereby the valve is opened at a predetermined point.

2. An internal combustion engine comprising a base, a cylinder slidably mounted therein, a piston in the cylinder, a crank 40 shaft, the cylinder and piston being operatively connected therewith to move in relatively opposite directions, a spring seated puppet valve adapted to move upwardly positioned vertically in the underside of the 45 cylinder ahead of the piston, a roller on the end of the stem of the valve, a lever arm pivotally mounted to the base and whose upper surface is adjacent the roller, means whereby the lever arm is normally pressed 50 downward, and a cam under the lever arm frictionally engaged therewith whereby the lever arm and valve are raised at a predetermined point.

In testimony whereof I affix my signature. 55
THOMAS H. BURNETT.
